SIGNALING AND INDICATING DEVICE FOR PROTECTING THE MOLDS AND MOLD LINERS OF TYPESETTING MACHINES

Application filed May 31, 1929. Serial No. 367,429.

This invention relates to typesetting machines commonly known as linotype machines, and comprehends an attachment therefor which is designed to assist the operators and machinists in preventing injury to the molds and mold liners.

Whenever it is necessary for the operator to change the size of the mold, particularly as to the length of the line which is being cast, it is essential to change the ejector blade in order to avoid injury to the liner. In changing over the machine from one size to another, the operator is required to make seven or eight different changes, including the change in the mold liner or liners and the change in the ejector blade. It is, therefore, evident that not infrequently the operator fails to make the corresponding change in the ejector blade, which results in bending or other injuries to the liner and to the mold or trimming knives. Once a liner is hit by the ejector blade, it is practically worthless and necessitates the expense of replacement. However, the expense of replacement is of minor importance as compared with the inconvenience, and sometimes the impossibility, of obtaining a new liner within a reasonable time for the completion of the work in hand. Also, in some instances, the operators or machinists attempt to straighten a bent liner which has been hit, but this results in improper seating and, hence, imperfection in the slugs which are subsequently cast, and involves the time and expense of scraping off or removing the overhang or fin which develops. Furthermore, there is the possibility of breakage of the mold, which runs into an expense of several hundred dollars. It is, therefore, evident that each time a liner is hit considerable time and expense are involved, which the present invention seeks to overcome.

Broadly, the invention contemplates an attachment which functions to produce a continuous signal whenever the mold turning pinion is pulled out to change a mold liner or to swing to another mold, which signal informs the operator that the corresponding ejector blade must be changed and which signal is discontinued by the operation of

changing the ejector blade, or, conversely, if the ejector blade is changed first, the continuous signal is produced, which signal is discontinued when the mold disk pinion is pulled out to change the mold or mold liners. 55

Another reason why the aforementioned difficulties and troubles develop lies in the fact that the markings on the mold liners are indistinct, difficult to read and in time become so illegible that the proper size is often mistaken for a wrong one. 60

It is, therefore, a further object of the present invention to provide an indicating device, by virtue of which the size of the mold liner being used is unmistakably displayed 65 to avoid mistakes.

More specifically, the invention comprehends a signaling device for the purpose specified which includes switches operable to close or open the circuit, which switches are actuated respectively by the movement of the mold disk pinion and by the ejector blade selecting means. 70

The indicating device includes a series of dials which are automatically brought into display position by turning of the mold disk, whereby the mold that is up or in the starting and ejecting position is clearly indicated by the dial which is displayed. 75

Among its other objects, the invention comprehends a signaling and indicating device of the character specified which is comparatively simple in its construction and mode of operation, inexpensive to manufacture and install and which is thoroughly reliable and highly efficient in its purpose. 80

With the above recited and other objects in view, reference is had to the following description and accompanying drawings, in which there is exhibited one example or embodiment of the invention, while the claims define the actual scope of the same. 85

In the drawings:

Figure 1 is a fragmentary front view of a typesetting machine equipped with signaling and indicating devices constructed in accordance with the invention. 95

Figure 2 is a fragmentary side view of the ejector blade selecting mechanism, illustrat- 100

ing the signal switch which cooperates therewith.

Figure 3 is an enlarged fragmentary front view illustrating the arrangement of the 5 signaling switches on the machine and the operating connection between the mold disk gear and the indicating device.

Figure 4 is a fragmentary side elevation 10 illustrating the location of the signal switch which is operated by movement of the mold disk pinion.

Figure 5 is a diagrammatic view of the signaling circuit, including the switches.

Figure 6 is an enlarged front view of the 15 indicating dial and its operating mechanism.

Figure 7 is a side view thereof.

Figure 8 is a sectional plan view taken approximately on the line indicated at 8-8 in Figure 6.

Figure 9 is an enlarged fragmentary sectional view taken approximately on the line 20 9-9 of Figure 1.

Figure 10 is a fragmentary side view of the 25 signal switch which works in connection with an ejector blade selecting mechanism of a different form of typesetting machine.

In the drawings, A designates the mold disk of a typesetting machine which is provided with the usual mold bases B, mold caps C and constant and variable mold liners D 30 and E. The mold disk is also provided with the usual gear F which is mechanically driven through the medium of the mold disk pinion shaft G when the mold disk pinion H is coupled to the shaft through the clutch pin I engaging in the mold disk pinion flange J. The manual turning of the mold disk is accomplished by means of a knob K carried by the pinion assemblage, so that when the 35 knob is moved outwardly the clutch pin is disengaged from the flange J, permitting the operator to freely rotate the pinion H for turning the mold disk. In the form of typesetting machine with which the invention is 40 illustrated, the ejector blade selecting mechanism, which is designated generally by the reference character L, includes a locking lever M which must be depressed to permit of the selection of the desired ejector blade, and in 45 accordance with the present invention a switch 10 is installed at this point which is provided with a movable switch arm 11 adapted to be selectively moved into contact with a pair of spaced contacts 12 and 13 50 upon successive depressions of an actuating button 14 which is disposed directly under and adapted to be actuated by depressions of the lever M. The signal 15, which may 55 be either of the visual or audible type, is installed on the typesetting machine at any desired point, and said signal is arranged in a circuit which includes a source of supply 60 from which a conductor 17 leads through the signal 15, thence to the switch arm 11. A second switch 18 is supported adjacent

the mold disk pinion, and the switch 18 is provided with a switch arm 19 which is selectively moved into engagement with spaced contacts 20 and 21 by successive depressions of the actuator button 22. The actuator button is depressed by a lever 23 which is fulcrumed as at 24, and said lever is shifted by and with the mold disk pinion when the knob K is pulled out by the operator. The circuit includes a second conductor 25 which leads to the switch arm 19 of the switch 18. The contacts 20 and 13 are connected by a conductor 26, and the contacts 21 and 12 are connected by a conductor 27. It, therefore, follows that when the operator desires to 70 change the mold liner, the knob K is grasped and pulled out to manually turn the mold disk to the position for making the change. When the knob is pulled out to shift the mold disk pinion, the switch lever 23 is moved into contact with the actuator button 22 of the switch 18. Assuming the circuit illustrated in Figure 5 to be in the open condition shown, the depression of the actuator button 22 will cause the switch arm 19 to be 75 moved from its engagement with contact 20 to a position in engagement with contact 21. This will close the signaling circuit and energize the signal 15, due to the fact that the current will flow from the source of supply 80 16 through the conductor 25, through switch arm 19, contact 20, conductor 27, contact 12, switch arm 11 and back to the source of supply through the conductor 17 which leads 85 through the signal 15. Obviously, the signal will remain energized and indicate to the operator that the ejector blade should be changed. When the operator depresses the locking lever M to permit of the changing 90 of the ejector blade, the downward movement of said lever M will depress the actuator button 14 of the switch 10, thereby moving the switch arm 11 of the switch 10 from its engagement with contact 12 to its engagement 95 with contact 13, thus breaking the circuit and deenergizing the signal. On the other hand, if the operator initially changes the ejector blade before changing the mold liner, the circuit will be closed originally by 100 the operation of the switch 10 and will be 105 opened when the operator pulls out on the knob K for the purpose of changing the mold liner. It is, therefore, apparent that a signaling device has been devised, by virtue of which the operator is warned against failing to change the mold liners and ejector 110 blades coincidently.

In order to render the signaling device applicable to other forms of typesetting machines than that particularly illustrated in 125 Figures 1 to 4 of the drawings, there is shown in Figure 10 a different form of ejector blade selecting mechanism which includes a lever N having a detent O which cooperates with a rack P. In this instance, the switch 10 is 130

supported directly by the lever N and the actuator button 14 of the switch 10 is depressed by means of a lever 28 which is fulcrumed as at 29 on the lever N and which lever 28 has a terminal 30 which is held out of engagement with the actuator button 14 by the weight of the lever handle 28. When the operator desires to manipulate the lever N, he grasps the detent O and the lever 28, thereby depressing the actuator button 14 of the switch 10 for either making or breaking the signaling circuit, as the case may be. In some instances, in older types of machines where the ejector blades are changed by hand, it is proposed to provide at a point adjacent the ejector blade, a switch 10 which must be manually operated, to discontinue the signal. Due to the fact that the operator's hand is brought so close to the ejector blade in cutting off the signal, it is obvious that his attention will be attracted to the ejector blade and will prompt him to make the required change.

The indicating device by virtue of which the reading of the size of the mold liners is greatly facilitated consists of a rotary member 35 which is preferably in the nature of an annulus having a central hub portion 36 and radial spokes 37. The annulus or rim and spokes support a plurality of pairs of relatively rotatable dials 38 and 39 bearing respectively indicia 40 and 41. The member 35, together with its dials, is rotatably mounted on an arbor 42 which is supported by a bracket 43 directly in rear of the assembling elevator Q of the machine and in such a manner that one pair of dials 40 and 41 is exposed to the view of the operator. In practice, four pairs of dials are provided, corresponding to the four molds on the mold disk, and the member 35 is operatively connected with the mold disk for turning movement coincident therewith. This connection, as illustrated, consists of a ring gear 44 carried by the member 35 which meshes with a gear 45 journaled at 46 for rotation on the bracket 43. A pinion 47 meshes with the gear 45 and is connected by a flexible shaft 48 to a pinion 49 which in turn meshes with the mold disk gear F. The pinion 49 is journaled for rotation in a shiftable bearing yoke 50 which is fulcrumed at 51 and which is normally urged in a direction to engage the teeth of the pinion 49 with the teeth of the mold disk gear F by means of a spring 52.

In practice, after the operator changes his mold and ejector and continues to complete the making of the necessary changes, he changes the long finger. At this point, the member 35 is near by and it requires but a few instants to rotate the pairs of dials 38 and 39 to bring the desired combination of indicia 40 and 41 in a relation which indicates the size of the corresponding mold disk. It thus follows that after the pairs of dials

have been properly set, the operator will have directly in front of him means which indicates the mold disk which is up, whereby the same may be readily compared with the indicator R which designates the ejector blade which is in operative position. A glance at the two indicating devices will inform the operator as to whether the proper ejector blade is being used with the mold which is up.

From the foregoing, it will, therefore, be apparent that a typesetting or linotype machine which is equipped with the signaling and indicating device in accordance with the invention, will practically eliminate the breaking or bending of mold liners or other damage to the machine by signaling or indicating the operator to prevent, first, their forgetting to change the ejector blade after changing the mold liner; second, by forgetting to change the mold liner after changing the ejector blade; third, by swinging their mold disk to put another mold up and forgetting to change the blade; fourth, by mistaking the size of the liner due to its being obliterated or to the difficulty of reading the size on the mold liners.

What is claimed is:

1. An attachment for linotype machines including means operable to produce a continuous signal by setting of the mold disk pinion for manipulation and means operable by manipulation of the ejector blade changing mechanism for discontinuing said signal.

2. An attachment for linotype machines comprising means operable to produce a continuous signal either by setting of the mold disk pinion for manipulation or manipulation of the ejector blade changing mechanism.

3. An attachment for linotype machines comprising means operable to produce a continuous signal either by setting of the mold disk pinion for manipulation or manipulation of the ejector blade changing mechanism and means for discontinuing said signal.

4. An attachment for linotype machines comprising means operable to produce a continuous signal either by setting of the mold disk pinion for manipulation or manipulation of the ejector blade changing mechanism and means for discontinuing said signal located adjacent the mold disk pinion and the ejector blade changing mechanism respectively.

5. In a linotype machine including means shiftable to a position for manually turning the mold disk and manually shiftable means for selecting the ejector blades; signaling mechanism operable to render a continuous signal by the initial shifting of one of said means and operable to discontinue the signal upon the subsequent shifting of the other means.

6. In a linotype machine including means shiftable to a position for manually turning

the mold disk and manually shiftable means for selecting the ejector blades; signaling mechanism operable to render a continuous signal by the initial shifting of one of said means and operable to discontinue the signal upon the subsequent shifting of the other means, said signaling mechanism consisting of a circuit including a signal adapted to be continuously operative when the circuit is closed and a pair of switches in said circuit operable upon successive actuations to make and break the circuit.

7. In a linotype machine including means shiftable to a position to permit of manual turning of the mold disk and manually shiftable means for selecting the ejector blades; signaling mechanism consisting of a circuit including a signal adapted to be continuously operative when the circuit is closed and a pair of switches located respectively adjacent said means and operable respectively by the successive shifting of said means to close and open said circuit as and for the purpose specified.

8. The combination with a linotype machine which include means shiftable to a position for permitting of the manual turning of the mold disk and manually shiftable means for selecting the ejector blades, of a signaling circuit including a signal adapted to be continuously operative when the circuit is closed and a pair of two-way switches located respectively adjacent said means and operable respectively by the same for closing and opening the circuit upon successive operations of said means.

9. A signaling attachment for linotype machines including a signal and means operable to render the signal active and inactive by the successive setting of the mold disk pinion for manual turning and the manipulation of the ejector blade changing mechanism.

10. An attachment for linotype machines including a signal, means operable to produce a continuous actuation of the signal either by performing the operations of setting the mold disk pinion for manual turning or by manipulating the ejector blade changing means and means operable to discontinue the signal by subsequently performing the other operation.

11. An attachment for linotype machines including a signal, means operable to produce a continuous actuation of the signal either by performing the operation of setting the mold disk pinion for manual turning or by manipulating the ejector blade changing means, said means operable to discontinue the signal by subsequently performing the other operation and a mold liner size indicator movable by and coincident with the mold disk for selectively displaying the size of the mold which is up and a common manipulating means for actuating said signal and indicator.

12. A safety attachment for protecting the molds, mold liners and ejector blades of linotype machines including a mold liner size indicator movable by and coincident with the mold disk for selectively displaying the size of the mold which is up and a signal and means operable to produce a continuous actuation of the signal either by performing the operation of setting the mold disk pinion for manual turning or by manipulating the ejector blade changing means, said means being operable to discontinue the signal by subsequently performing the other operation and a common manipulating means for actuating said indicator and for producing or discontinuing the signal by performing the operation of the setting of the mold disk pinion for manual turning.

13. The combination with a linotype machine, of an attachment therefor including a signal and means operable by the manual setting of the mold disk of the machine for rendering said signal continuously active.

14. The combination with a linotype machine, of an attachment therefor including a signal and means operable by the manual setting of the mold disk of the machine for rendering said signal continuously active and means for rendering said signal inactive.

15. The combination with a linotype machine, of an attachment therefor including a signal and means operable by the manual setting of the mold disk of the machine for rendering said signal continuously active and means located adjacent the ejector blade for rendering said signal inactive.

Signed at New York in the county of New York and State of New York this 28th day of May, A. D. 1929.
